UNITED STATES PATENT OFFICE.

HORACE G. JOHNSTON, OF CORSICANA, TEXAS.

WELL-SINKING APPARATUS.

SPECIFICATION forming part of Letters Patent No. 779,285, dated January 3, 1905.

Application filed October 26, 1904. Serial No. 230,129.

To all whom it may concern:

Be it known that I, HORACE G. JOHNSTON, a citizen of the United States, residing at Corsicana, in the county of Navarro and State of Texas, have invented certain new and useful Improvements in Well-Sinking Apparatus; and I do hereby declare the following to be a full, clear, and exact description of the invention, such as will enable others skilled in the art to which it appertains to make and use the same.

This invention relates to improvements in a well - boring apparatus, and particularly to that style of apparatus which is provided with means for gripping a well - tube and turning the same, while permitting of a longitudinal movement of the well - tube through the gripping means.

The invention consists in certain novel constructions, combinations, and arrangements of parts, as will be herein described and specifically claimed.

In the accompanying drawings, Figure 1 is a top plan view of a well - boring apparatus embodying the features of the present invention. Fig. 2 is a side elevation of the same, a portion thereof being shown in section. Fig. 3 is an enlarged detail horizontal sectional view taken upon the line of one of the 30 bolts or screw - rods for tightening the well - tube gripping mechanism, the said rod carrying the grippers and forcing them against the well - tube when drawn toward the same. Fig. 4 is an enlarged detail view in elevation of one of the connecting - blocks employed in the gripping mechanism. Fig. 5 is a transverse vertical section taken through one of the blocks and parts inclosed thereby.

In operating well - drilling casings or tubes, as well as rods, by means of a gripping mechanism which engages the outer surface of the boring means for turning it it frequently happens that only an imperfect hold can be obtained upon the said drilling means, because of irregularities in the shape thereof and the consequent imperfect grip which it is possible to obtain with the usual well - drilling apparatus. It is desirable, upon the other hand, to obtain as perfect a grip or hold upon the 45 boring - tube as possible, for otherwise the

gripping apparatus is in danger of slipping at intervals upon the boring tube or casing, tending to injure or cut the said tube or unduly wear the biting edges of the gripping mechanism. The boring apparatus forming 55 the subject of the present invention is so formed that the gripping means can accommodate itself to various unevenness which may occur in well tubes or rods, the gripping mechanism being of that type in which the 60 well tube or rod is clamped by means of gripping devices which permit the rod or tubing to descend as the bore of the well is deepened.

In the drawings I have shown a preferred way of constructing my improved well - boring 65 mechanism, 1 indicating a stationary base plate or table, and 2 a rotating upper plate or turn - table, each being provided with a central aperture 3, through which the well - tube 4 passes vertically. Antifriction - bearings 5 70 of any desired construction are arranged between the upper and lower plates, being held in place and guided in movement by grooves or runways formed in the opposing faces of the said plates. The upper plate or turn - table 2 is provided with an annular overhanging portion formed with a beveled gear 6 upon its under surface, which is engaged by a beveled pinion 7. The beveled pinion 7 is secured to an actuating - shaft 8, which may be connected in any usual or well - known manner with power mechanism for driving it.

The gripping means for engaging the well tube or boring device is mounted upon the turn - table or top plate 2, and while it is so secured thereon that it may accommodate itself to unevennesses in the contour of the tube it is secured thereon so that it cannot rise from the upper surface of the table 2, and the gripping mechanism cannot, therefore, have a 85 vertical movement with respect to the turn - table. For the purpose of securing the gripping means upon the turn - table vertical pins or studs 10 are mounted thereon. The studs or pins may be secured in any desired manner to the turn - table 2, but are preferably fastened to bosses 9, which project upwardly from the upper surface of the table a sufficient height to support the gripper - holding mechanism in operative position. The holding 95 100

and adjusting means for the grippers comprise screw-threaded bars or rods 12, formed with stud-engaging means in their central portions. Such stud-engaging means consists in an apertured hub portion 11, made to fit upon the stud 10. The rod 12 is prevented from rising upon the pin or stud 10 by inserting a spring cotter-pin 13 through an aperture formed in the said pin or stud immediately above the central hub or bearing portion 11. In this manner the securing-bars 12 have an axial movement upon the pins 10 in a plane parallel with the turn-table, but are prevented from rising from the turn-table and the bosses 9. The studs or pins 10 are oppositely arranged upon the table 2, and the bars 12 project in opposite directions from the point of their bearing upon the pins or studs 10. The outer ends of said bars are screw-threaded and extend into connecting-blocks 14 for movably connecting the grippers with the said bars. The connecting members or blocks 14 project low enough at one or more points to engage and rest upon the upper surface of the table 2, as at 15, thus steadyng the whole mechanism and giving it a positive bearing and support upon the table. Nut-sleeves 16, having internal threads for engaging the threads upon the bars 12, have a bearing in the outer parts of the connecting members or blocks 14. The outer ends of the nut-sleeves are provided with suitable means for rotating them, such means being shown in the drawings in the shape of hand-wheels 17. The hubs of said wheels 17 bear upon the outer ends of the blocks or connecting members 14, so that when the hand-wheels are rotated the nut-sleeves 16 will also be rotated, and the blocks or connecting members 14 may be drawn toward the central bearing of the bars 12 and the studs or pins 10. The ends of the sleeves 16 are provided with a nut-shaped portion 18, to which may be applied any suitable implement or wrench for operating the said sleeve, if preferred, instead of employing the hand-wheels for this purpose. The sleeves 16 are provided with annular grooves 16^a, which are preferably engaged by the inner ends of screws 16^b. The screws 16^b extend through the walls of the connecting-blocks, and their inner ends, which are rounded and made comparatively smooth, project a sufficient distance into the grooves 16^a to insure the retracting of the connecting-blocks 14 when the nut-sleeves 16 are reversed or screwed outwardly upon the ends of the bars 12. The drill rod or tube is engaged by gripping jaws or rings 19, which are mounted upon gripper shafts or rods 20. The gripping rings 19 are preferably mounted, revolvably upon the gripper-shafts 20, so that when the sharp edges of the said rings engage the surface of the well-tube, as shown in Fig. 1, the well-tube may be rotated by the turning of the table 2, and yet the tube may descend between the grippers as the well-bore deepens, the gripping-rings rotating to accommodate such descent. The gripping-jaws 19 are so mounted upon the shafts 20 that they may be arranged quite close together or farther apart, as desired, so as to properly grip various sizes of drill-tubes. The spacing of the gripping-jaws 19 is effected by the use of washers 21, which are slipped upon the shafts 20, a suitable number being placed between the jaws to spread them the right distance apart and others being placed outside the jaws to insure the holding of the said jaws centrally. The shafts 20 are so connected with the connecting members or blocks 14 that the gripping means may accommodate themselves to irregularity or unevenness upon the surface of the well-tube or drill-rod. As shown in Fig. 3, each of the rods or shafts 20 is passed through a bearing 22, formed in the connecting member or block 14. The bearing 22 at its central portion is circular, so as to fit quite closely upon the end of the shaft 20, the said bearing being flared outwardly in a horizontal plane, as indicated in Figs. 3 and 4. The engagement of the shaft with the double tapered bearing 22 at each end is such that the shaft and connecting member or blocks may have movement in a horizontal plane with respect to each other, the shaft assuming different angles with respect to the blocks under the action of uneven or irregular surfaces upon the well-tube and the consequent alteration or lateral movement of the gripping-jaws. By reference to Fig. 1 it will be seen that the normal position of the parts arranged upon the turn-table is such as to form a rectangular figure, the shafts 20 extending generally at right angles to the carrying-bars 12. Because, however, of the pivoted connection between the carrying-bars 12 and the pins or studs 10 and the swivel connection between the connecting members or blocks 14 and the adjacent ends of the shafts 20 the figure formed by the said carrying-bars and shafts may be altered from a rectangular shape to that of a rhomb or a rhomboid. The gripping means thus constructed is of a superior character, for it makes it possible to obtain a continuous positive hold upon the well tube or casing and yet permit of the longitudinal movement of the said casing with respect to the gripping means. Without the swivel action if an uneven place upon the well-tube is encountered by the jaws one or more of the said jaws may be forced out of engagement with the surface of the well-tube and the grip upon the same be thus weakened. The gripping device may thus slip with respect to the casing or well-tube and cause the said gripping means to tend to cut the drill-tube annularly. Such action is also detrimental to the sharp cutting edges of the gripping-jaws. Such difficulties are entirely obviated by the construction above described, since the whole

gripping mechanism can accommodate itself to various shapes or uneven places upon a well-tube, so that all the gripping-jaws may maintain a biting or gripping contact with the well-tube.

- It will be seen from the above description that the gripping device or grippers are adjustably carried by the ends of the carrying-bars 12 and that the said carrying-bars are connected with the table by means of the pins 10. It is only necessary, therefore, to rotate the table 2 by means of the actuating-pinion 7 to carry the grippers around and rotate the well-tube engaging the same. The pivotal connection of the shafts 12 with the table through the agent of the pins 10 makes it possible for the bars to swing laterally over the surface of the table, the said bars, however, having no vertical movement with respect to the table, because of the cotter-pins or other securing means applied to the upper ends of the pins 10. The adjustment of the sleeves 16 operates to draw the grippers toward the well shaft or tube and effect the gripping thereof for turning the well shaft or tube. The pivotal movement of the bars 12 is accommodated by the connection through the blocks 14 with the shaft 20, so that the swiveling movement of the parts is complete.
- 30 In the construction set forth is embodied a gripping means for well-boring apparatus which is capable of engaging a well-tube so that it may rotate it and yet permit of its longitudinal movement through the gripping means. The lateral swiveling movement renders the device more effective and more capable of adapting itself to various well tubes or casings which may be used.

Having now described my invention, what I claim as new, and desire to secure by Letters Patent, is—

1. A well-boring apparatus comprising a rotary plate or table, gripping means mounted thereon for engaging a well tube or shaft, the said gripping means being capable of a swiveling action with respect to the table for accommodating unevenness in the well tube or shaft.
2. A well-boring apparatus, comprising a rotating plate or table, grippers mounted thereon, and means permitting a swiveling action between said plate and grippers for connecting the grippers to the table, and means for preventing the grippers from rising from the table.

3. A well-boring apparatus comprising a rotating table or plate, grippers mounted thereon, carrying means pivotally connected with the table, and connecting means interposed between the carrying means and the grippers, said connecting means permitting

of a swiveling movement between the grippers and the carrying means.

4. A well-boring apparatus comprising a rotating plate or table, gripper-carrying bars pivotally mounted thereon, the said bars having movement in a plane parallel with the table, grippers mounted between the carrying-bars and connecting-blocks interposed between the grippers and carrying-bars, the said connecting-blocks having a tapering bearing engaging the gripping devices and permitting of a swiveling action between the grippers and the carrying-bars.

5. A well-boring apparatus provided with a rotating plate, studs or pins rising from the plate, carrying-bars having a central bearing engaging the said pins or studs, means engaging the pins or studs above the bearings for preventing the carrying-bars from rising from the table or plate, and grippers connected pivotally with the carrying-bars, the said bars having a lateral swinging movement over the plate.

6. A well-boring apparatus comprising a plate or turn-table, carrying-bars pivotally mounted thereon, grippers arranged between the carrying-bars, the said grippers being made up of well-tube-engaging jaws, and shafts for carrying the same, connecting or coupling members having bearings for engaging the ends of the carrying-bars and bearings for engaging the ends of the gripper-shafts, the said latter bearings being flared outwardly from their central portions for permitting a swiveling action of the parts.

7. A rotating mechanism for a well-boring apparatus comprising grippers, a holding means for carrying the same, connecting members or blocks interposed between the grippers and the holding means, each of said blocks having a swiveled bearing formed therein for engaging the gripping means, and a rotating support carrying the gripper-holding means and actuating the same.

8. A gripping device for well-boring apparatus comprising pivoted carrying-bars, swivel-blocks mounted on the ends of the carrier-bars, adjusting sleeve-nuts for regulating the position of the swivel-blocks upon the carrier-bars, the said blocks having transversely-arranged bearings, the said bearings flaring outwardly from their shaft-engaging portions, gripper-shafts engaging the bearings, and well-tube-engaging jaws carried by the said shafts.

In testimony whereof I affix my signature in presence of two witnesses.

HORACE G. JOHNSTON.
